(74) Attorney, Agent, or Firm — Rankin, Hill & Clark LLP

(57) **CLAIM**

The ornamental design for a bottle straw lid, as shown and described.

DESCRIPTION

FIG. 1 is a perspective view of a bottle straw lid according to our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a bottom plan view of FIG. 1.

The broken lines in the drawings depict portions of the bottle straw lid that form no part of the claimed design.

1 Claim, 7 Drawing Sheets(56)
